CARTRIDGE CARTON

Oscar Eggebrecht, Wausau, Karl Koehler, Neenah, and Frank J. Gruber, Jr., Menasha, Wis., assignors to Marathon Paper Mills Company, Rothschild, Wis., a corporation of Wisconsin

Application November 27, 1942, Serial No. 467,090

5 Claims. (Cl. 229—27)

This invention relates to a carton formed from a single blank adapted for packaging articles such as cartridges and the like.

The packaging and shipping of cartridges and also various fragile articles has presented for a long time very serious problems in preventing accidents occurring during shipment which might cause loss or damage. According to the present invention, a carton is formed from a single blank which is provided with receiving portions for snugly and securely retaining a plurality of articles packaged in a single carton so that they will be securely retained in position and will not come in contact with each other during shipment thereby preventing damage or explosion of cartridges or breakage of fragile articles which may be packaged in the carton.

Further details of the construction will be apparent from the following specification and drawings wherein:

Figure 1 is a plan view of the blank from which the carton is made.

Figure 2 is a perspective view of the blank partially folded and glued.

Figure 3 is a perspective view of the completed carton in flat folded condition as shipped to the user.

Figure 4 is a perspective view of the carton illustrating the first step in setting same up, and

Figure 5 is a perspective view illustrating the final step in setting up the carton.

Referring to the drawings, the carton is made from a single blank of cardboard or other suitable sheet material cut and scored as shown in Figure 1 to provide a rear panel 20, a front panel 22, a bottom panel 30 and side panels 21 and 23. A glue panel 29 is hingedly connected to rear panel 20 along score line 1. A cover 24 is hingedly connected to upper edge of rear wall 20 along score line 11. An auxiliary bottom panel 25 is hingedly connected to the lower edge of the rear panel 20 along score line 18. Hingedly connected to the panel 25 is a front auxiliary panel 26 hingedly connected thereto along score line 26'. An article-retaining panel 27 is hingedly connected to the front auxiliary panel along score line 14. Panel 27 is provided with a series of cut out circular openings 15, for example, which are adapted to snugly receive cartridges or cut out in any desired contour to conform and snugly receive any other articles desired to be packaged in the carton. Panel 21 is retained in a plane parallel to the bottom panel, but if desired may be retained in any suitable position

depending upon the positioning of sustaining panel 28.

A sustaining panel 28 is hingedly connected to the article-retaining panel 15 along score line 16. Panel 28 is adhesively secured to the rear panel 20 as illustrated in Figure 2. Side panel 21 is hingedly connected to the rear panel 20 along score line 2. The closure flap 32 is hingedly connected to the lower edge of panel 21 along score line 8. Closure flap 32 is preferably cut at one edge along a beveled line 10. The closure flap is separated from the adjacent panel 30 along a cut and score line 9. The bottom panel 30 is hingedly connected to the lower edge of the front panel 22 along a score line 6. A tongue portion 33 hinged along score line 7 at the lower edge of the bottom panel 30 is provided for locking the bottom panel into position when the carton is set up. The bottom panel 30 is separated from the adjacent end flap 31 along a score line 30'. The second side panel 23 is hingedly connected to the front panel 22 along score line 4. The closure flap 31 is hingedly connected to the lower edge of the panel 23 along score line 5. Closure flap 31 is cut away at an inclined line 31'.

In forming the carton from the blank previously described, the front auxiliary panel 26 is folded along score line 26' against the body portion of the carton and the retaining panel 28 is folded back along score line 16 and glued to the inner face of the rear panel in the relation as indicated in Figure 2. The glue panel 29 is then adhesively attached to an overlapping edge portion of the side panel 23 in the position shown in Figure 3. The carton in this flat condition, as illustrated in Figure 3, is then ready for shipment to the user.

In setting up the carton, the auxiliary bottom panel 25 is first folded up along score line 18 at right angles to the rear wall 20. This automatically brings the front auxiliary panel 26 at right angles to the bottom wall 25 and at the same time brings the article-retaining panel 27 into a plane parallel with the bottom panel 25 as shown in Figure 2. Closure flaps 31 and 32 are then folded over and brought into contact with the bottom panel 25 in the position shown in Figure 5. Tongue 33 of the bottom panel 30 is then inserted in slit 17 whereby the bottom panel 30 is securely locked and retained in position. The articles to be packaged in the carton are then placed in the cut-out portions 15 and the cover 24 is then adhesively attached to the front cover by means of a piece of tape 50 or by

any other suitable means. If desired, the cover 24 may be provided with end flaps or locking portions in any known suitable manner instead of utilizing the tape for sealing the carton.

According to the present construction the articles packaged in this carton are securely retained in position. The positioning of the bottom auxiliary panel 25 in face contact with the bottom panel 30 reinforces the bottom of the carton and it will therefore safely sustain heavy articles placed therein. Similarly, the lower portion of the front panel 22 is reinforced by virtue of the front auxiliary panel 26 being in face contact therewith. This construction thus provides a very rigid and strong construction for packaging articles.

It is intended to include modifications and changes of the specific embodiment previously described which embody the essential features of the invention within the scope of the appended claims.

We claim:

1. A collapsible carton made from a single blank comprising a front, rear, bottom, and side panels, and an article supporting extension integrally hinged to the bottom edge of the rear panel consisting of a bottom auxiliary panel having dimensions substantially that of the horizontal cross-sectional dimensions of the carton, a front auxiliary panel, an article-retaining panel having the same dimensions as the bottom panel extending from the front to the rear panel and a sustaining panel adhered to the rear panel, all said panels being integrally hinged along suitably spaced fold lines, said bottom auxiliary panel being adapted to be positioned in face contact with the inner face of the said bottom panel, said front auxiliary panel being adapted to be positioned in face contact with the inner face of the said front wall, said carton being adapted to be set up for use by folding said bottom auxiliary panel at right angles to the said rear panel.

2. A collapsible carton made from a single blank comprising a front, rear, bottom, and side panels, and an article supporting extension integrally hinged to the bottom edge of the rear panel consisting of a bottom auxiliary panel, having dimensions substantially that of the horizontal cross-sectional dimensions of the carton, a front auxiliary panel, an article-retaining panel having the same dimensions as the bottom panel extending from the front to the rear panel and in a plane parallel to the bottom panel, and a sustaining panel adhered to the rear panel, all said panels being integrally hinged along suitably spaced fold lines, said bottom auxiliary panel being adapted to be positioned in face contact with the inner face of the said bottom panel, said front auxiliary panel being adapted to be positioned in face contact with the inner face of the said front wall, said carton being adapted to be set up for use by folding said bottom auxiliary panel at right angles to the said rear panel.

3. A collapsible carton made from a single blank comprising a front, rear, bottom, and side panels, and an article supporting extension integrally hinged to the bottom edge of the rear panel consisting of a bottom auxiliary panel having dimensions substantially that of the horizontal cross-sectional dimensions of the carton, a front auxiliary panel, an article-retaining panel

having the same dimensions as the bottom panel and a sustaining panel adhered to the rear panel, all said panels being integrally hinged along suitably spaced fold lines, said bottom auxiliary panel being coextensive in area with the said bottom panel and adapted to be positioned in face contact with the inner face of the said bottom panel, said front auxiliary panel being adapted to be positioned in face contact with the inner face of the said front wall, said carton being adapted to be set up for use by folding said bottom auxiliary panel at right angles to the said rear panel.

4. A collapsible carton made from a single blank comprising a front, rear, bottom, and side panels, a glue panel hingedly connected to the rear panel and adhesively secured to an overlapping portion of the adjacent side panel, and an article supporting extension integrally hinged to the bottom edge of the rear panel consisting of a bottom auxiliary panel having dimensions substantially that of the horizontal cross-sectional dimensions of the carton, a front auxiliary panel, an article-retaining panel having the same dimensions as the bottom panel and a sustaining panel adhered to the rear panel, all said panels being integrally hinged along suitably spaced fold lines, said bottom auxiliary panel being adapted to be positioned in face contact with the inner face of the said bottom panel, said front auxiliary panel being adapted to be positioned in face contact with the inner face of the said front wall, said carton being adapted to be set up for use by folding said bottom auxiliary panel at right angles to the said rear panel.

5. A collapsible carton formed from a single blank comprising a rear panel, a glue panel hingedly connected to the longitudinal edge of said rear panel, a side panel hingedly connected to other longitudinal edge of said rear panel, a front panel hingedly connected to said side panel, a second side panel hingedly connected to said front wall, a closure flap hingedly connected to the lower edge of said second side panel, a bottom panel hingedly connected to the bottom edge of said front panel, a locking tongue provided at the free edge of said bottom panel, a closure flap hingedly connected to the lower edge of said first side panel, a cover hingedly connected to the upper edge of said rear panel, an article supporting extension hingedly connected to the bottom edge of said rear panel consisting of a bottom auxiliary panel having dimensions substantially that of the horizontal cross-sectional dimensions of the carton adapted to be positioned in face contact with the inner face of the said bottom panel, a front auxiliary panel adapted to be positioned in flat face contact with the inner face of said front panel, an article-retaining panel extending from the front to the rear panel having the same dimensions as the bottom panel, and a sustaining panel adhered to the rear panel, said carton being adapted to be set up for use by folding said bottom auxiliary panel at right angles to the said rear panel, all said panels being integrally hinged along suitably spaced fold lines, and a slit in the hinge line connecting the rear panel and the bottom auxiliary panel for receiving said locking tongue.
